DESIGN FOR A SUN HAT

Edward Wittcoff, University City, Mo.

Application October 13, 1933, Serial No. 49,476

Term of patent 3½ years

To all whom it may concern:

Be it known that I, EDWARD WITTCOFF, a citizen of the United States, residing at 7220 Pershing Avenue, University City, in the county of St. Louis, and State of Missouri, have invented a new, original, and ornamental Design for Sun Hats, of which the following is a specification, reference being had to the accompanying drawing, forming part thereof.

Figure 1 of the drawing is a top plan view of the hat showing the design; and
Figure 2 is a sectional view thereof.

I claim:

The ornamental design for a sun hat, as shown.

EDWARD WITTCOFF.
